UNITED STATES PATENT OFFICE.

ALBERT HÖCHSTER, OF NEW YORK, N. Y.

DESIGN FOR A BATTERY-CELL.

SPECIFICATION forming part of Design No. 26,840, dated March 30, 1897.

Application filed November 12, 1896. Serial No. 611,889. Term of patent 14 years.

To all whom it may concern:

Be it known that I, ALBERT HÖCHSTER, a citizen of the United States, and a resident of the city and county of New York, State of New York, have invented a certain new, useful, and original Design for Battery-Cells, of which the following is a specification, reference being had to the accompanying drawings, which form part of the same.

10 The invention relates to a design for battery-cells; and it consists in the novel configuration or shape herein specifically shown and claimed.

In the accompanying drawings, Figure 1 is a plan view of a battery-cell embodying my new design, and Fig. 2 is a perspective view of the same.

The characteristic feature of my design con-

sists in the configuration and shape of the battery-cell shown, comprising the two sector-shaped ends *a a* of substantially equal dimensions, the two flat sides *b b* of rectangular outline, and the uniformly cylindrically-curved side *c*, the upper sector-shaped end being sunken within a marginal rim except at a medial upward projection *d*.

What I claim, and desire to secure by Letters Patent, is—

The design for a battery-cell comprising the design substantially as shown.

Signed at New York, N. Y., this 10th day of November, 1896.

ALBERT HÖCHSTER.
